UNITED STATES PATENT OFFICE.

EDMUND CURTIS PEARSON AND JAMES CHILDS, OF WESTMINSTER, LONDON, ENGLAND,
ASSIGNORS TO VICKERS LIMITED, OF WESTMINSTER, ENGLAND, A BRITISH COMPANY.

SLIPS FOR SUPPORTING DRILL PIPES IN WELL-BORING APPARATUS.

Application filed November 7, 1925, Serial No. 67,480, and in Great Britain November 27, 1924.

This invention relates to slips for supporting drill pipes in well-boring apparatus.

In one form of apparatus for well-boring in which the necessary power is derived from a rotary machine, the boring bit or tool is attached to the lowest one of a number of connected lengths of drill pipe, which drill pipe is in turn screwed to a drive stem of square cross section. This stem passes through a drive bushing fitted into a master bushing, which latter is in turn fitted into a recess in the table of the rotary machine. The whole length of drill pipe and the square stem can be raised and lowered, being for example suspended by a wire rope from a block at the top of a derrick provided with hoisting gear. As the drilling progresses it becomes necessary from time to time to add further lengths of drill pipe to the end of the connected succession or string of pipes in the hole. To enable this addition to be accomplished, the square drive stem is raised along with the drive bushing, bringing the string of pipes up through the table of the machine. It is necessary to support the length of pipes in the hole by means other than the overhead block, and for this purpose fittings called slips made in vertically divided halves are placed in a tapered hole in the master bushing, the said slips having horizontal teeth in contact with the pipe.

It is frequently found, however, that the drill pipes are not truly circular on their outer circumference, and it is an object of this invention to ensure that the total weight of the string of pipes shall be evenly distributed notwithstanding the occurrence of such irregularities, thereby avoiding damage to the pipes.

According to this invention the tapered annular slips, which are as usual radially divided into halves, or otherwise into a plurality of independently movable members, have on their inner surfaces inclined recesses, wherein segments of hardened steel are capable of sliding up and down, the said segments projecting beyond the inner surfaces of the slips and having horizontal or helical teeth adapted to grip the drill pipe to resist the descent thereof. When the slips are lifted each segment is pulled to the top of its travel by a bolt passing through a retaining plate and secured to a lifting plate;

and when the slips are lowered into the tapered hole in the table of the rotary drilling machine so as to surround the drill pipe, each segment is free to fall by gravity to the bottom of its travel, or so far as is permitted by the opposing surface of the pipe. The segments are thus self-adjusting, not only to differences of diameter but also to departures from the truly circular form of the pipe, so that the load is evenly distributed between all the segments. When the slips are lifted the segments automatically open out to their maximum radius, thereby freeing themselves from the pipe.

It has previously been proposed, in a pipe lifter having hinged jaws closing on the pipe, to provide toothed segments separately adjustable in inclined recesses in the jaws, but these segments were set by screws to suit a variable but known diameter of pipe instead of being self-adjusting by gravity as in the present invention, and were driven upwards and supported by springs, instead of being lifted in unison by a lifting plate when disengaging the pipe.

In order that the said invention may be clearly understood and readily carried into effect, the same will now be described more fully with reference to the accompanying drawings, in which:—

Figure 1 represents in elevation one slip of a pair, provided with horizontally toothed segments.

Figure 2 is a plan of the said slip.

Figure 3 is an elevation of a pair of slips viewed from a direction at right angles in relation to the view in Figure 1, a portion of one of these slips being represented in section on the line 3—3 in Figure 2.

Figure 4 represents in elevation a slip provided with helically toothed segments.

The slips A, A' may be castings turned to a conical shape on their exterior surfaces. The segments B may be prevented by a retaining plate C, secured to the tops of the slips, from rising out of the tapered slots D which are machined in the bore of the slips. Above the retaining plate is a lifting plate E provided with one or more handles F, and bolts or screws G passing through elongated clearance holes H in both the lifting plate E and the retaining plate C are screwed into each of the segments, so that when the slips are raised from the ground by the said

handle the segments B are thereby automatically pulled to the tops of the slots D in the slips. The slips are then lowered by hand into the tapered hole in the master bushing and embrace the pipe, and the handle F is then released. If the pipe is truly circular and of the correct size the segments B will remain in their highest positions in the slots; but should the pipe not be truly circular certain segments will fall downwards and inwards until all the segments are in contact with the pipe. The string of drill pipes is then slightly lowered, when the teeth of the segments bite into the metal 15 of the pipe and support the whole weight of the string of pipes.

When the additional length of drill pipe has been attached to the string of pipes in the hole the square drive stem is again attached to the string of pipes and the full weight taken on the wire rope. The whole string of pipes is then raised a short distance by means of the hoist on the derrick. This causes the toothed segments B to press 25 against the retaining plate C so that the slips are lifted off their seating in the master bushing, and the slips can then be removed by hand.

Means are provided to prevent the toothed segments B from falling down the well in the event of the lifting screws G breaking. For example a pin J (Figure 3) may be screwed into the back of each toothed segment B, its head projecting into a groove 35 in the slip, and a stop K is cast across each groove, the pin J being located an appreciable distance above the stop so that the normal movements of the segments are not affected thereby.

40 By the use of slips according to this invention the following advantages are obtained, in comparison with slips having integral teeth:—The toothed segments working in tapered slots are free to adjust themselves to the irregularities of the drill pipe, so that the load is evenly distributed between all the segments. These segments can

easily be removed and replaced, thus eliminating the difficulties caused by dull slips and loss of time in re-sharpening the teeth 50 thereof. It is only necessary that the segments themselves should be made of hardened steel, as the body of the slips may be of a material which is cheaper and more easily machined.

55 In the following claims, the expression "substantially horizontal teeth" must be understood to include teeth which are actually horizontal as illustrated in Figure 1, or helical as illustrated in Figure 4.

60 What we claim and desire to secure by Letters Patent of the United States is:—

In well boring apparatus arcuate slips adapted to be fitted into a tapered hole in the table of a rotary drilling machine for 65 temporarily holding drill pipes in one position, each of said slips being provided with a plurality of independently movable members, said movable members being composed of segments of hardened steel capable of 70 sliding up and down in inclined recesses on the inner surfaces of the slip members, each segment projecting beyond the inner surface of its slip member and having substantially horizontal teeth adapted to grip the drill 75 pipe to resist the descent thereof, a retaining plate secured to the top of each slip member, a lifting plate located above said retaining plate and having a handle, bolts passing through elongated clearance holes in both 80 the lifting plate and retaining plate, said bolts being secured to the segments, whereby the segments are automatically pulled to the top of their travel when said handle is raised to lift the slip member, and said bolts 85 being of such length as to allow each segment to fall by gravity independently of adjacent segments when said handle is released until all the segments bear against the pipe, whereby the load is distributed over 90 all said segments irrespective of whether the outside of the pipe be truly circular.

EDM. C. PEARSON.
JAMES CHILDS.
